DELIVERY INDICATOR

John J. Choffin and Andrew J. Augustine,
Geneva, N. Y.

Application June 23, 1948, Serial No. 147,137

Term of patent 7 years

(Cl. D1—2)

To all whom it may concern:

Be it known, that we, John J. Choffin and Andrew J. Augustine, both citizens of the United States, residing at Geneva, in the county of Ontario and State of New York, have invented a new, original, and ornamental Design for Delivery Indicators, of which the following is a specification, reference being had to the accompanying drawing, forming part thereof.

In the drawing:

Fig. 1 is a view in front elevation of a delivery indicator, showing our new design.

Fig. 2 is a view in side elevation.

Fig. 3 is a top plan view.

Fig. 4 is a bottom view.

The dominant features of our design reside in the portions shown in full lines.

We claim:

The ornamental design for a delivery indicator, as shown and described.

JOHN J. CHOIFFIN.
ANDREW J. AUGUSTINE.
